INVENTOR

BY *Wm. C. L. Johnson*

ATTORNEYS

UNITED STATES PATENT OFFICE.

GEORGE C. SEYMOUR, OF BROOKLYN, NEW YORK.

HEEL.

Application filed May 31, 1921. Serial No. 473,679.

To all whom it may concern:

Be it known that I, GEORGE C. SEYMOUR, a citizen of the United States, and a resident of the city of New York, borough of Brooklyn, in the county of Kings and State of New York, have invented a new and Improved Heel, of which the following is a full, clear, and exact description.

This invention relates to foot wear and particularly to an improved removable heel section and has for an object to provide a construction which may be readily removed and replaced at any time.

Another object of the invention is to provide an improved rubber heel section and associated parts whereby the rubber section readily interlocks with the remaining part of the heel when in use but permits a quick and easy assemble.

20 A further object of the invention is to provide a detachable or removable rubber heel section capable of adaptation to a large heel or a very small heel either of leather or wood.

A still further object of the invention is to provide a removable rubber heel section in which the parts are so formed as to require a knife or other similar instrument to remove.

In the accompanying drawing—

30 Figure 1 is a perspective view of the rear part of a shoe with a heel embodying the invention shown applied thereto.

Figure 2 is a sectional view through Figure 1 on line 2—2.

35 Figure 3 is a sectional view through Figure 1 on line 3—3.

Figure 4 is a bottom plan view of the heel shown in Figure 1 with the rubber section removed.

40 Figure 5 is a plan view of the inner surface or interlocking portion of the rubber section of the heel shown in Figure 1.

Figure 6 is a perspective view of the structure shown in Figure 1 with the locking flange applied thereto illustrating how the flange of the rubber section co-acts with the locking plate.

Figure 7 is a perspective view similar to Figure 6 but showing the parts in the position immediately previous to the removal of the rubber section.

50 Figure 8 is a view similar to Figure 6 but showing a slightly modified form of the invention and the application of the invention 55 to a different shaped heel.

Figure 9 is a view similar to Figure 8 but showing the rubber section partially removed.

Figure 10 is an inverted perspective view of part of a wooden heel with a slight modified form of the invention shown applied thereto.

Figure 11 is a sectional view through Figure 10 approximately on line 11—11.

Figure 12 is an inverted perspective view 65 of the retaining sleeve shown in Figures 10 and 11.

Figure 13 is a perspective view of the upper or locking face of the rubber section shown in Figures 10 and 11. 70

Referring to the accompanying drawing by numerals, 1 indicates a shoe of any desired kind and 2 the heel thereof which is provided with a rubber heel section 3 and a locking plate 4. The plate 4 may be of metal, fiber or any desired material and is secured to the heel 2 by screws or other desirable means. The heel 2 is preferably formed with a recess 5 for receiving part of the heel section 3 as shown in Figure 2 80 whereby the flange 6 of the heel section 3 may interlock with the locking plate 4. The heel 2 may be leather, wood or other desired material and if desired may be covered with a suitable covering 7. In forming the rubber section 3 preferably the section is formed from a solid block of a good grade of rubber and is provided with an upstanding section 8 which merges into the flange 6. The body of the section 3 is slit 85 so as to produce a tongue 9, which tongue if desired may be chamfered or slightly cut away at 10 and 11 to permit a more ready swinging or distortion of the end of the section as shown in Figure 7 whereby the 90 flange 6 may be readily removed from the fastener plate 4.

It will be noted that the front and corners of the flange 6 are contracted to such an extent as to permit the entire portion 8 to be 100 pulled through the opening 12 and the locking plate 4. When the tongue 9 is in its assembled or correct position as shown in Figure 1, the rubber section 3 cannot be removed but when a knife or other similar instrument is inserted between the end of the tongue and the remaining part of section 3 and then pulled downwardly from the position shown in Figure 1, the rubber section 3 105 may be readily and quickly removed without 110

injury to any of the parts. When it is desired to replace the rubber section 3 the tongue 9 is left in the position shown in Figure 7 and one corner of the flange 6 is inserted and then the entire heel swung around to its correct position so that the remaining part of the flange may be crowded readily into the socket 5 and beneath the locking plate 4. After this has been done the tongue 9 is then forced back into its correct position as shown in Figure 1 and the section 3 is then in condition for use. Most people wear their heels off on one side and, consequently, it causes a much longer life to the section 3 when the same may be removed from one heel and placed on the opposite heel. This may be readily done by the construction just described without injuring any parts and without waiting for the section 3 to be uniformly worn.

In some instances the heel of the shoe is not constructed as shown in Figure 1 but is made larger and sometimes is arranged with one side of the heel extending further towards the toe than the opposite side of the heel. In Figures 8 and 9 a construction is shown which will take care of the heel of the kind just mentioned. In fact the device may be used in connection with any desired shaped heel without departing from the spirit of the invention. Where the heel is comparatively large and irregularly shaped the heel section 3 is made in two parts but otherwise the construction is identical in principle. As shown in Figure 9 the rear part 13 remains fixed while the front part 14 is removed. The removal is made in the same manner as in the preferred form of the invention, namely, by pulling downwardly on the tongue 9 which will contract the flanges and permit a ready removal of said front part. The rear part 13 may then be collapsed slightly and readily removed.

In Figures 10 to 13 inclusive will be seen another slightly modified form of the invention in which the device is adapted particularly for use in connection with wood heels. The ordinary wood heel tapers downwardly until it is very small at the lower end so that an ordinary locking plate similar to plate 4 could not be used. To provide a locking plate which will be feasible for a small ended heel, an annular band structure 16 is provided which fits into a notched portion 17 of the heel 15 said annular member 16 being formed with an inturned flange 18 acting similar to the overhanging or flange section 6' of plate 4. Preferably the annular member 16 is provided with a groove 19 in which part of the ornamental covering 20 may be forced. If desired, an adhesive may be used to assist in retaining the end portion of covering 20 in the groove 19 whereby not only is the heel 15 covered with a silk or other covering member but also the band 16. The

rubber section 3'' is provided and formed as shown particularly in Figures 10 and 13 though it could be formed the same as shown in Figure 1. In the form shown in Figures 10 and 13 the tongue 9' is arranged transversely of the heel rather than longitudinally and acts to pull down one corner and part of one side of the flange 6 when the tongue has been moved outwardly as shown in Figure 7.

In all forms of the heel a form of socket is produced with an overhanging flange which is designed to co-act with a flange extending from the rubber heel section. In all forms of the rubber heel section a tongue is provided which may be manipulated for contracting certain parts of the rubber section in order to permit an easy and ready removal or replacement.

What I claim is:—

1. A heel of the character described comprising a heel body, an attaching plate connected to the heel body and a rubber section formed with means interengaging with said attaching plate, said rubber section being also formed with a tongue forming a part of the lift of said section normally acting to prevent the disengagement of said interengaging means and said plate, said tongue being displaceable from its normal position for permitting the disengagement of said attaching plate and the means interengaging therewith.

2. In a heel, a rubber attachment comprising an attaching plate having an overhanging portion and a rubber section formed with a flange interengaging with said overhanging portion, said rubber section being formed with a tongue positioned substantially centrally thereof forming a part of the tread surface of said section and adapted to prevent disengagement of said flange from said attaching plate, said flange and said tongue being of such a construction that if the tongue is displaced from its normal position the flange will be permitted disengagement from said attaching plate.

3. In an attachment for heels, an attaching plate formed with an opening therein and a rubber section formed with a projection having an overlapping flange adapted to overlap part of said attaching plate, said section being formed with means for normally preventing disengagement of said flange from said attaching plate, said means being capable of displacement from its normal position whereby said flange will be permitted disengagement from said attaching plate, and said rubber section being capable of being displaced so as to occupy the space formerly occupied by said means.

4. In a heel attachment for shoes, an attaching plate and a rubber section associated with said plate, said section being formed in two parts, both forming at one

of their faces the tread surfaces of the section, each part being provided with a flange interengaging with said plate and one of said parts being distortable and capable 5 of being swung to a plane transverse to the tread surface of said rubber section.

5. In an attachment for a heel provided with a recess a band adapted to be connected to the heel and overhang said recess, 10 and a rubber section formed with an interengaging flange adapted to engage the portion of said band overhanging said recess, said rubber section being provided with a tongue positioned so as to form a part of 15 the tread surface of said section and is adapted to prevent disengagement of said flange from said band, the tongue and the flange being so constructed that when the tongue is displaced from its normal position, 20 said flange is permitted disengagement from said band, and said section is per-

mitted to be displaced over the space formerly occupied by said tongue.

6. A heel for shoes comprising a body formed with a recess at the lower end, an 25 annular fitting positioned to overhang said recess, means for securing said fitting to said body and a rubber section formed with a flange interengaging with the overhanging portion of said fitting, said rubber section 30 being also formed with a tongue normally forming a part of the tread surface of said rubber section, said tongue extending transversely of the heel and positioned to normally prevent the disengagement of said 35 flange from said fitting, said tongue being displaceable from its normal position whereby said flange will be permitted disengagement from said fitting, and said section will be permitted to occupy the space formerly 40 occupied by said tongue.

GEORGE C. SEYMOUR.
